UNITED STATES PATENT OFFICE.

ALBERT A. HARVIE, OF OTTUMWA, IOWA.

KNOCKDOWN CARPENTER'S SQUARE.

1,049,299.

Specification of Letters Patent.

Patented Dec. 31, 1912.

Application filed March 2, 1912. Serial No. 681,138.

To all whom it may concern:

Be it known that I, ALBERT A. HARVIE, a citizen of the United States, residing at Ottumwa, in the county of Wapello and State of Iowa, have invented certain new and useful Improvements in Knockdown Carpenters' Squares, of which the following is a specification.

This invention relates to a knock-down carpenter's square; that is to a carpenter's square, in which the blade and tongue are made separate, but in which means are provided for joining them together and securing them at right angles to each other.

The application has particular reference to that class of knock-down square, in which the tongue and blade each constitutes practically a straight piece of material, so that the two parts can be easily packed into a carpenter's kit, and can be easily manufactured.

The present invention has reference particularly to the means for joining the tongue and blade together. For this purpose, I desire to provide a locking arrangement, so that by tightening a single screw or nut the two elements will be rigidly joined together at exactly the proper angle.

Other objects and uses will appear from a detailed description of the invention which consists in the features of construction and combination of parts hereinafter described and claimed.

In the drawing, Figure 1 shows a face view of the corner of the square, the tongue and blade being locked together; Fig. 2 shows a face view of the end of a tongue disengaged from the blade; Fig. 3 shows a face view of the end of the blade disengaged from the tongue; Fig. 4 is a section taken on the line 4—4 of Fig. 1, looking in the direction of the arrows; and Fig. 5 is a section taken on the line of Fig. 1, also looking in the direction of the arrows.

In the drawings, the numeral 6 designates the blade of the square, and the numeral 7 designates the tongue. In the construction illustrated, I have shown the locking member as being applied to the tongue, and other elements being correspondingly formed. It will soon be apparent, however, that the arrangement might be reversed, and that it is not necessary that the locking member should be applied to the tongue. In the construction illustrated, a channel 8 is formed across the blade, the same having its

side walls 9 and 10 beveled outwardly to receive the edges of the end of the tongue. A notch 11 is cut in from the outer edge of the blade, the same having its edge 12 beveled at an acute angle to the channel of the blade. There is provided a channel 13 across the face of the tongue, the edge 14 of said channel being undercut to match up with the edge 12 of the blade. The end portion 60 15 of the tongue is of proper size to seat nicely into the notch 11. The edges 16 and 17 of the tongue should be beveled to seat accurately against the faces 9 and 10 of the channel in the blade, and to make tight contact with them before the faces of the channels in the tongue and blade come together. It is preferred also that the edge 18 of the blade should be undercut slightly, the edge 19 of the tongue being cut at a similar angle. 70 75

By forming the parts as above stated, and proportioning them in substantially the manner stated, when the locking screw is tightened it will tend to wedge the blade over sidewise to bring its edge 12 tightly 80 against the edge 14 of the tongue. Also by reason of the bevel on the head of the screw, the side of the blade adjacent the screw will be drawn toward the tongue so as to seat the side walls 9 and 10 of the blade tightly and 85 squarely against the edges 16 and 17 of the tongue.

I provide a locking device for holding the two elements together after the tongue has been hooked into the blade. The preferred construction, that illustrated, comprises a headed screw 20 threaded into the tongue, and having its head 21 of a size to overlie a portion of the blade. It is preferred that this head should be beveled, as 90 95 shown in Fig. 5, so that by threading the screw tightly into place the elements will be drawn together, and at the same time there will be a tendency to force the blade sidewise so as to insure a tight contact between the edges 12 and 14. A notch 22 should preferably be formed in the blade to receive the overlying portion of the screw. In order to permit the square to be knocked-down without having to completely withdraw the screw, the head of the latter may be cut away in the portion 23, so that by 100 105 rotating the screw into the position shown in Fig. 2, the blade can be unhooked from the tongue.

As before stated, it is not necessary that the locking member should be applied to

the tongue, as it is obvious that the arrangement might be reversed, the locking member in this case being applied to the blade. In other words, the element 6 might be called 5 the tongue, and the element 7 the blade.

I claim:

1. In a knock-down carpenter's square, the combination of a blade having a channel extending across one of its faces, and 10 having the side walls of the channel outwardly beveled, and having the edge of the channel beveled at an acute angle to the face thereof, a tongue having a channel extending across the complementary face 15 thereof, and having the edges of the tongue beveled to correspond to the side walls of the channel of the blade, and having the edge of the channel of the tongue undercut to engage the edge of the channel of the 20 blade, and means for locking the tongue and blade together adjacent one edge of the channel of the tongue, the tongue being of such width with respect to the channel of the blade that the edges of the tongue engage 25 the edges of the blade channel before the faces of the channels come into contact, substantially as described.
2. In a knock-down carpenter's square, the combination of a blade having a channel 30 extending across one face thereof, and having one edge of the blade beveled at an acute angle to the face of the channel thereof, a tongue having a channel extending across the complementary face thereof, and

having one edge of said channel undercut 35 to engage the acute edge of the blade, and a headed screw on the tongue having the head thereof overlying the adjacent edge of the blade and adapted when threaded into place to draw the tongue and blade together and force the blade sidewise to bring the acute edge thereof into firm engagement with the undercut edge of the tongue channel, substantially as described. 40

3. In a knock-down carpenter's square, 45 the combination of a blade having a channel extending across one face thereof, and having one edge of the blade extending at an acute angle to the face of the channel thereof, a tongue having a channel extending 50 across the complementary face thereof, and having one edge of the channel of the tongue undercut to engage the acute edge of the blade, and a headed screw on the tongue having the edge of the head thereof outwardly beveled and adapted to overlie 55 a portion of the edge of the blade, whereby when said screw is tightened, the tongue and blade are drawn together, and the blade is forced sidewise to bring its acute edge 60 into firm engagement with the undercut edge of the tongue, substantially as described. 65
